US0D1085014S

(12) **United States Design Patent** (10) **Patent No.:** **US D1,085,014 S**
(45) **Date of Patent:** **** Jul. 22, 2025**

(54) **EARPHONE ADAPTER**

(71) Applicant: **Anker Innovations Technology Co., Ltd.**, Changsha (CN)

(72) Inventors: **Wu Xu**, Shenzhen (CN); **Zheng Wei**, Shenzhen (CN)

(73) Assignee: **Anker Innovations Technology Co., Ltd.**, Changsha (CN)

(**) Term: **15 Years**

(21) Appl. No.: **29/860,266**

(22) Filed: **Nov. 17, 2022**

(30) **Foreign Application Priority Data**

May 19, 2022 (CN) 202230298284.2

(57) **CLAIM**

The ornamental design for an earphone adapter as shown and described.

DESCRIPTION

FIG. 1 is a front-top perspective view of an earphone adapter showing our new design;

FIG. 2 is a rear-bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines depicting the remainder of the earphone adapter form no part of the claimed design.

1 Claim, 8 Drawing Sheets
